QUATERNARY NITROGEN COMPOUNDS

Gerhard Balle, Frankfort-on-the-Main, and Karl Horst, Hofheim in Taunus, Germany, assignors, by mesne assignments, to General Aniline & Film Corporation, New York, N. Y., a corporation of Delaware

No Drawing. Application March 3, 1939, Serial No. 259,632. In Germany October 10, 1935

6 Claims. (Cl. 260—561)

The present invention relates to quaternary nitrogen compounds.

In U. S. application Serial No. 104,334, filed October 6, 1938, of which this application is a continuation - in - part, quaternary ammonium compounds are described which are obtainable by causing halogen carboxylic acids or a salt or an ester thereof to react with a disubstituted aminoacylamide.

We have found that quaternary nitrogen compounds in which several carboxylic groups or their functional derivatives are united through carbon links with the quaternary nitrogen atom, are manufactured by causing a halogen carboxylic acid amide to act upon a disubstituted aminoacylamide obtainable, for instance, by reaction of halogenacylamides with secondary amines according to the scheme.

wherein R_3 stands for an aliphatic hydrocarbon radical, R_1 and R_2 stand for lower aliphatic hydrocarbon radicals which may be substituted and R_4 and R_5 stand for hydrogen or a hydrocarbon radical which may be substituted.

The formation of the quaternary nitrogen compounds according to the present invention corresponds to the following scheme:

wherein R_1 , R_2 , R_3 , R_4 and R_5 have the above-mentioned signification, R_6 represents an aliphatic hydrocarbon radical and X stands for amidated COOH.

The two components may be caused to react in the presence or absence of a suitable solvent or diluent, for example, in water or in an organic solvent, generally at a temperature of 30° C.—120° C. Depending on the nature of the parent materials, the reaction takes place already when mixing the reaction agents or heating under pressure may be necessary.

The amidated quaternary compounds may be further obtained by causing a halogen carboxylic acid ester to react with a disubstituted aminoacylamide and by causing the quaternary ammonium compound thus formed which contains esterified COOH to react with ammonia or a pri-

mary or secondary amine of the aliphatic, cycloaliphatic or aromatic series. In this way the ester group of the quaternary ammonium compounds containing esterified COOH, which are described in the parent application, are transformed into compounds containing amidated COOH.

Disubstituted amino-acylamides suitable for the reaction are for example: dimethylaminoacetobutyl-amide, dimethylamino-aceto-oleylamide, dimethylamino-aceto-methylstearyl amide, beta-diethylaminopropionyl-dodecylamide, alpha-dimethylaminostearoylamide.

These disubstituted amino-acylamides may be obtained in a smooth reaction by causing a secondary amine to react with a halogen-amide, for example: chloracetic acid butylamide, alpha-chloropropionic acid ethanolamide, beta-chloropropionic acid diethanolamide, chloracetic acid paratoluidide, chloracetic acid stearylamide, the amide mixture from chloracetic acid and the primary amines obtainable from palmnut oil fatty acid, chloracetic acid methylstearyl amide, alpha-chloropropionic acid oleyl-amide, alpha-bromo-stearic acid amide and others. The reaction with the secondary amines proceeds in some cases without external heat supply, and so rapidly that the heat evolved must be led away, and in other cases the components must be heated together, under pressure if necessary. The reaction may also be carried out in the presence of solvents. The application of an agent for binding hydrogen halide is useful, if the secondary base is not used in excess.

Halogen carboxylic acid amides suitable for the reaction with the afore-mentioned aminoacylamides are, for example:

Furthermore, the condensation may first be carried out with aliphatic halogen-carboxylic acid esters, for instance:

60 and when the reaction is complete the esterified

COOH-group is transformed into the amidated COOH-group by treatment with ammonia, a primary or secondary amine. This transformation may be carried out by mixing the two components, if desired in an inert solvent. The aminolysis takes in some cases an exothermic course; in some cases heating, if required with application of pressure, may be necessary.

The number of the components suitable for the manufacture of the quaternary nitrogen compounds is not limited to the above-named compounds. There may also be used amino-acylamides disubstituted in the amino-groups by aryl or aralkyl; the amide radical may also contain any other substituents. Furthermore, there may be used any halogen-carboxylic acid which contains a reactive halogen atom.

The quaternary nitrogen compounds obtainable by the present invention are in the pure state colorless, in part crystallizable, in part oily to fatty- or wax-like bodies which in general are soluble in water or, especially those of high molecular weight, disperse in water so as to form an emulsion. Uses of these compounds are as softeners for textiles and as agents for the improvement of the fastness qualities of substantive dyeings.

The new nitrogen compounds are, for instance, suitable for use in the textile industry.

The following examples serve to illustrate the invention, but they are not intended to limit it thereto; the parts are by weight:

1. 168 parts of dimethylamino-acetostearyl-
amide are melted together with 130 parts of
chloracetododecylamide for 4 hours at 90° C. to
120° C., while stirring, until a sample of the product
is soluble in warm water or disperses therein
so as to form an emulsion. The yield of N-di-
methyl-N-acetostearylamide - betaine - dodecyl-
amide chloride of the formula:

is quantitative. The anhydrous product has a wax-like structure.

The dimethylamino-acetostearylamide is obtained by treating in a pressure vessel for 3 hours at a temperature of 80° C. to 100° C. 328 parts of chloracetostearylamide with 220 parts of a solution of dimethylamine of 45 per cent. strength. After distillation of the solvent, the dimethylamine hydrochloride formed as by-product is extracted by means of hot water (with addition of sodium chloride) at 85° C. The separated oil solidifies after cooling and is pure dimethylamino-acetostearylamide. The yield almost corresponds with that foretold by theory.

2. 102 parts of dimethylamidoacetamide and 360 parts of chloracetomethylstearylamine in 500 parts of benzene are boiled for about 5 to 7 hours in a reflux apparatus. On cooling the reaction product precipitates from the benzene solution from which it may be separated by filtering or pouring off. The residual solvent may be eliminated by heating under reduced pressure. The remaining fat-like mass dissolves in water to a clear solution.

3. 298 parts of dibutylaminoacetodibutylamide are mixed with 205 parts of chloracetodibutylamide; the addition occurs thereby with evolution of heat, care being taken that the temperature does not rise above about 80° C. to 100° C. The product obtained is soluble in neutral, acid and alkaline solutions.

4. 188 parts of beta-diethylamino-propionic acid-hydroxy-ethylamide and 108 parts of chloroacetic acid methylester are heated to about 70° to 80° C., reaction occurring thereby. In case 5 the temperature rises rapidly the vessel must be cooled from outside so that the temperature does not exceed about 100° C. to 120° C.

The ester chloride obtained having the formula:

15 is mixed with a solution of 270 parts of oleylamine in 500 parts of benzene and then heated for several hours on the water bath in a reflux apparatus. After the benzene as well as the methanol formed during the reaction have been distilled, a colorless watersoluble product is obtained.

20 5. 178 parts of dimethylamino-acetanilide and 275 parts of beta-chloropropionic acid dodecylamide are heated together to about 80° C. to 100° C., while stirring, until the product has become soluble in water. A feebly colored fat-like mass is obtained, whose solutions in water have a strong foaming action.

25 6. 212 parts of dimethylamino-acetoethylcyclohexylamide and 180 parts of chloroacetic acid diethanolamide are heated together, while stirring, to about 80° C. to 100° C., until the reaction product has become soluble in water.

30 7. 158 parts of dipropyl aminoacetamide are heated together with 180 parts of chloroaceto-benzyl amide to about 70° C. to 90° C. until the mass has become watersoluble.

35 Instead of chloroacetobenzylamide there may be used 161 parts of chloroacetopiperidide; a watersoluble product is likewise obtained thereby.

40 8. 158 parts of alpha-dimethylaminobutyric acid dimethylamide are melted at 90° C. to 100° C. together with 260 parts of chloroacetic acid dodecylamide, until the mass has become soluble in water. A fat-like, almost colorless product 45 is obtained.

9. 102 parts of dimethylaminoacetamide are melted at 100° C. to 120° C. together with 315 parts of alpha-chloro-stearic acid amide, until the reaction mixture has become watersoluble. 50 The product thus obtained is an almost colorless fat-like mass.

We claim:

1. The products of the general formula:

60 wherein R₁ and R₂ represent lower aliphatic hydrocarbon radicals, R₄ and R₅ represent members of the group consisting of hydrogen, hydrocarbon radicals and aliphatic hydrocarbon radicals substituted by hydroxy-groups, R₃ and R₆ represent aliphatic hydrocarbon radicals, and X means amidated COOH.

65 2. The products of the general formula:

75 wherein R₁ and R₂ represent lower aliphatic hydrocarbon radicals, R₃ and R₅ represent aliphatic hydrocarbon radicals, R₄ is a member of

the group consisting of hydrogen, hydrocarbon radicals and aliphatic hydrocarbon radicals substituted by hydroxy groups, R₅ represents an aliphatic hydrocarbon radical of at least 8 carbon atoms and X means amidated COOH.

3. The products of the general formula:

5

10

15

wherein R₁ and R₂ represent lower aliphatic hydrocarbon radicals, R₅ represents an aliphatic hydrocarbon radical of at least 8 carbon atoms and X means amidated COOH.

4. The product of the formula:

5. The product of the formula:

6. The product of the formula:

GERHARD BALLE.
KARL HORST.
